UNITED STATES PATENT OFFICE

HARRY W. HOLLAND, OF ELIZABETH, NEW JERSEY, ASSIGNOR TO THE TEXAS COMPANY, OF NEW YORK, N. Y., A CORPORATION OF DELAWARE

DESIGN FOR A SERVICE STATION CART

Application filed November 12, 1931. Serial No. 41,706. Term of patent 14 years.

To all whom it may concern:

Be it known that I, HARRY W. HOLLAND, a citizen of the United States, residing at No. 1 Raymond Terrace, in the city of Elizabeth, county of Union, and State of New Jersey, have invented a new, original, and ornamental Design for Service Station Carts, of which the following is a specification, reference being had to the accompanying drawing, forming part thereof.

The figure is a perspective view of a service

station cart, showing my new design, the exterior face of the opposite display panel being substantially like that of the one shown in full face, and the triangular space between the two display panels being open at the rear end of the cart.

I claim:

The ornamental design for a service station cart, as shown and described.

HARRY W. HOLLAND.
